UNITED STATES PATENT OFFICE.

JOSEPH H. REDMOND, OF SAN FRANCISCO, CALIFORNIA.

SHEAVE-BLOCK.

SPECIFICATION forming part of Letters Patent No. 360,050, dated March 29, 1887.

Application filed November 18, 1886. Serial No. 219,326. (No model.)

To all whom it may concern:

Be it known that I, JOSEPH H. REDMOND, of San Francisco, State of California, have invented a new and Improved Sheave-Block for 5 Hoisting and other Purposes, of which the following is a specification.

The invention relates to all the various patterns of sheave-blocks where the improvement may be found applicable; and it consists in 10 the method of hanging the sheave in the block, by which the block, as a whole, and the sheave in particular, is rendered more durable and a large amount of friction is avoided in operating.

15 In the accompanying drawings, forming part of this specification, Figure 1 is a sectional elevation taken on a vertical line cutting through the axis of the sheave. Fig. 2 is a side view of the block.

20 In both figures the same letters of reference are used to indicate the same parts.

The usual method of hanging the sheaves in these blocks is to arrange a fixed spindle to rest in the side cheeks of the block and 25 allow the sheave to loosely revolve upon it. In this way, owing to the necessarily-narrow bearing, which can be no wider than the space between the cheeks of the block, or equal to the distance through the hub of the sheave, 30 and because of the difficulty of properly lubricating this bearing, which is often allowed to run dry, the hub of the sheave is subject to rapid wear, so that when heavy work is done the sheave of a new block frequently commences to wobble after a few hours' use, and often in consequence the sheave bears hard 35 against the side cheeks of the block at its periphery, cutting away the wood and causing excessive friction. Then the sheave has to be 40 taken out and rebushed at considerable expense and loss of time.

The present invention is designed to obviate this difficulty and reduce the friction to a minimum by a system of thorough lubrication, and 45 by giving increased width of bearing for the spindle-journals distributes the necessary friction over a more extended surface, and thus minimizes its wearing action, to the effect of greatly increasing the life of the block.

50 In the drawings, A A are the cheeks of the

block; B B, the parting-strips; C C C C, the bolts which fasten these together.

D D are the rope-slings, within which the block is held.

E is the eye for the hanging hook, which it 55 is unnecessary to show.

F is the sheave over which the running-rope passes. G is its spindle, and H H are the boxes in which the spindle is supported and revolves. These boxes are made solid and 60 pass through the cheeks of the block, to bear against the hub of the sheave on one end, and out and beyond at the opposite end a little distance inside the ends of the spindle, the journals of which may be as long, within reasonable limits, as desired. The boxes have 65 flanges h, which extend sidewise to beyond the rope-slings, so that the bolts h' may be easily got at. These latter bolts should have their heads countersunk in the cheeks of the 70 block on the inside, as shown in dotted lines, Fig. 1.

The holes bored through the boxes to receive the spindle will serve, where the boxes extend beyond the spindle, as receptacles for a suitable inspissated lubricant, K, such as is used for carriage-axles. The outer circumference 75 of the boxes has at the end projecting outward a screw-thread, and a cap, I, also having a screw-thread cut within its interior, will 80 screw over it.

Along the spindle, at each end as far as the hub of the sheave, there is a little groove, i, 85 cut to permit the lubricant to reach the hub and lubricate adjoining surfaces of hub and box.

The caps I will be about half filled with the lubricant before being screwed on; also the space between the end of the spindle and end of the box will be filled.

The spindle is driven tightly in the hub of the sheave, and it may be, if preferred, either square where it passes through the sheave, or a trifle larger in diameter than the journals, so that there will be a shoulder on the spindle to 95 bear against the box on each side, and thus prevent any lateral motion, should there be a tendency to acquire it.

I am aware that the spindles of sheave-blocks have heretofore been constructed with 100

rotating spindles carried in boxes on each side of the sheave; and I do not broadly claim such a construction.

What I claim as my invention, and desire 5 to secure by Letters Patent, is as follows:

A sheave-block for hoisting, comprising the following parts: the wooden cheeks A A and parting-strips B, bolted together, rope-sling D, with eye E, separate elongated boxes H, carrying spindle G, said boxes having side flanges to bolt them to the cheeks A, the inner ends be-

ing made to pass through the cheeks and abut against the hub of the sheave, and the outer ends being provided with a lubricant-chamber formed by the caps I screwed thereon, sheave 15 F, and spindle G, firmly secured in the hub thereof, the whole arranged and operating substantially as described.

JOSEPH H. REDMOND.
